UNITED STATES PATENT OFFICE.

HENRY H. CUMMINGS, OF MALDEN, ASSIGNOR TO THE DAVIS-MOORE
SEWING MACHINE COMPANY, OF BOSTON, MASSACHUSETTS.

TAKE-UP FOR SEWING-MACHINES.

SPECIFICATION forming part of Letters Patent No. 447,009, dated February 24, 1891.

Original application filed March 26, 1890, Serial No. 345,432. Divided and this application filed July 3, 1890. Serial No. 357,635.
(No model.)

To all whom it may concern:

- Be it known that I, HENRY H. CUMMINGS, a citizen of the United States, residing at Malden, in the county of Middlesex and State 5 of Massachusetts, have invented certain new and useful Improvements in Take-Ups for Sewing-Machines, of which the following is a specification, reference being had thereto to the accompanying drawings.
- 10 My invention has for its object to provide an improved take-up mechanism for sewing-machines, my improved take-up being more especially intended for use on wax-thread or other machines designed for heavy work.
- 15 In the accompanying drawings, Figure 1 shows a side view of a wax-thread sewing-machine embodying my invention. Figs. 2 and 3 are detail side views, partly in section, of the take-up mechanism; and Fig. 4 is a 20 front end view of the latter. Fig. 5 is a detail section on line 5 5 of Fig 4.

A denotes the frame of the machine; B, the driving-shaft suitably journaled in said frame and provided near its rear end with a 25 grooved cam b.

The machine herein shown is fully illustrated and described in my application, Serial No. 345,432, filed March 26, 1890, of which this application is a division. It may be stated 30 here, generally, that this machine embraces a rotary shuttle and a hooked needle, both arranged below the work-plate and adapted for forming lock-stitches; but as the general features of this machine form no part of this application they need not be herein particularly described.

N is the take-up lever, provided between its ends with a pin or shaft n, which is rigid therewith and which is journaled in the frame 40 A. The take-up lever N thus has two arms on opposite sides of its pivot or fulcrum, the lower or take-up arm being preferably furnished with a roller n², around which the thread passes, as more clearly shown in Fig. 45 3, said roller co-operating with resistance-rollers o on stationary axes attached to the frame A. The upper arm of the take-up lever is provided with a pin m', on which is pivoted an arm or lever m, extending below the ful-

crum n of the take-up lever, and to the lower 50 end of which is attached the forward end of a connecting-rod K', the rear end of which latter is secured to the slotted upper end of an operating-lever K, receiving movements from the cam b on the driving-shaft B. The 55 lever m is provided with an arm or portion m², formed rigid therewith in any suitable manner. The pivot n of the take-up lever is provided with a hole n³, through which the thread passes, and forward of said hole on a 60 portion of the take-up lever just below the center of the fulcrum of the latter is a bearing portion n', over which the thread runs, said bearing portion being arranged to be engaged by the forward or free end of the arm 65 m² of the lever m, so that the said arm by pressing on said bearing portion or on the thread running over the same will impart a 70 backward or take-up movement to the lower arm of the lever N at the proper time. Thus 75 when the connecting-rod K' begins to move backward, drawing with it the lower end of the lever m, the free end of the arm m² is first pressed on the thread lying on the bearing portion n', thereby clamping the thread, and 80 as the said arm continues its downward or backward movement it forces the lower or take-up arm of the take-up lever backward, thus drawing up the thread to tighten a 85 stitch. As the movements of the take-up lever are thus derived from the thread-clamping arm m², it will be apparent that the greater the resistance or the harder the pull of the take-up on the thread the tighter the latter will be clamped between the arm m² and the 90 bearing portion n'. Thus the thread will 95 always be securely clamped to prevent it from being drawn from the thread-supply when the take-up lever is operating to tighten the stitches, provided there is any resistance on the thread. As, however, the thread is entirely slack when the take-up first begins to operate, it is desirable, in order that the thread will be properly clamped at this time, that the take-up lever should not move too easily, and to this end I preferably provide the pivot pin or shaft n with a friction device consisting, as herein shown, of a pin m", pressed against

said shaft by a spring m^5 , attached to the frame A by screws m^6 and m^8 , the latter serving to regulate the tension of said spring, so that the amount of friction on the shaft n 5 may be varied, as may be desired.

By providing the upper end of the take-up-operating lever K with a slot, so that the connection of the rod K' therewith may be changed, the throw of the take-up may be 10 varied, as may be desired. Adjustable stops L, attached to the arm or frame A and serving to prevent overthrowing of the take-up lever, are preferably employed. The forward movements of the take-up are effected by the 15 draft of the thread when the arm m^3 is raised or swung away from the bearing portion n' of the roller n , while the backward or take-up movements of said lever derived from the arm m^2 are positive.

Having thus described my invention, I 20 claim and desire to secure by Letters Patent—

1. In a sewing-machine, the combination, with the stitch-forming devices, of a take-up lever having a bearing portion over which 25 the thread passes, and an operating-lever, as m , serving to impart take-up movements to said take-up lever, said operating-lever being provided with an arm or portion arranged to press upon and clamp the thread at said 30 bearing portion and through such pressure to operate the take-up lever, whereby the greater the resistance on the thread and the harder the pull of the take-up the tighter the thread will be clamped.

2. In a sewing-machine, the combination, with the stitch-forming devices thereof, of a take-up lever having rigid therewith a fulcrum pin or shaft, and being also provided with a bearing portion over which the thread 40 passes, a friction device for the said fulcrum pin or shaft, and an operating-lever, as m , having an arm or portion arranged to press upon the thread at said bearing portion and through such pressure to operate the take-up 45 lever.

3. The combination, with the stitch-forming mechanism of a sewing-machine, of a take-up lever pivoted between its ends, and thus hav-

ing two arms, one of which serves to take up the loops of thread and the other of which 50 carries a pin, said take-up lever having a bearing portion over which the thread passes, and an operating-lever pivoted on said pin carried by the take-up lever and having an 55 arm or portion to press upon and clamp the thread at said bearing portion, and by such pressure to operate the said take-up lever, said operating-lever extending from said pin beyond the fulcrum of the take-up lever, and means for actuating said operating-lever. 60

4. The combination, with the stitch-forming mechanism of a sewing-machine and the frame thereof, of the take-up lever N, having between its ends the pivot pin or shaft n , rigid with said lever and journaled in said frame, 65 said take-up lever having at its upper end the pin m' and near its fulcrum the bearing portion n' , over which the thread passes, the operating-lever m , pivoted on said pin m' and having rigid therewith the arm m^2 , the free 70 end of which is arranged to press upon said bearing portion and through such pressure to operate the take-up lever, and means for actuating said operating-lever.

5. The combination, with the stitch-forming 75 mechanism of a sewing-machine and the frame thereof, of the take-up lever N, having between its ends the pivot pin or shaft n , rigid with said lever and journaled in said frame, 80 said take-up lever having at its upper end the pin m' and near its fulcrum the bearing portion n' , over which the thread passes, a friction device for preventing free movement of the said pin or shaft n , the operating-lever m , pivoted on said pin m' and having rigid 85 therewith the arm m^2 , the free end of which is arranged to press upon said bearing portion and through such pressure to operate the take-up lever, and means for actuating said operating-lever. 90

In testimony whereof I affix my signature in presence of two witnesses.

HENRY H. CUMMINGS.
